UNITED STATES PATENT OFFICE.

CHARLES N. MIKELS, OF NEWCASTLE, INDIANA.

DESIGN FOR AN EMBLEM-BADGE.

49,668.

Specification for Design. **Patented Sept. 19, 1916.**

Application filed July 17, 1916. Serial No. 109,836. Term of patent $3\frac{1}{2}$ years.

To all whom it may concern:

Be it known that I, CHARLES N. MIKELS, a citizen of the United States, residing at Newcastle, Henry county, and State of Indiana, have invented a new, original, and ornamental Design for Emblem-Badges, of which the following is a specification.

The figure shown in the drawing is a plan view of an emblem badge showing my new design.

I claim:

The ornamental design for an emblem badge as shown.

In witness whereof I have hereunto set my hand and seal at Indianapolis, Indiana, this 13th day of July, A. D. nineteen hundred and sixteen.

CHARLES N. MIKELS. [L. S.]

Witnesses:

A. C. RICE,
H. P. DOOLITTLE.
